To all whom it may concern:

- Be it known that I, CHARLES BOOZE, a citizen of the United States, residing at Buffalo, in the county of Erie and State of New York, have invented and produced a new and original Design for Wall-Paper, of which the following is a specification, reference being had to the accompanying photograph, forming part thereof.
- 10 The leading feature of my design consists of stencil-like sprays of flowers and leaves of the wild rose projecting from a scroll-like or cornucopia-shaped base made in stencil, as represented in the accompanying photograph.
- 15 A flower in full bloom is arranged centrally above the mouth of the ornamental base, and a branch or spray of leaves and flowers ex-

tends vertically from the ornamental base and above the center flower, and a branch or spray of leaves and flowers droops to one side 20 from the center flower. The ornamental scroll or cornucopia-shaped base and the sprays of flowers and leaves are placed at regular distances apart upon a background of tinted paper of any desired color. 25

What I claim is—
